J. Edw. Maybe

ATTY.

UNITED STATES PATENT OFFICE.

ERNEST AUSTIN HALL, OF TORONTO, ONTARIO, CANADA.

CYLINDRICAL GRINDING TOOL.

Application filed September 1, 1922. Serial No. 585,777.

To all whom it may concern:

Be it known that I, ERNEST A. HALL, of the city of Toronto, in the county of York, Province of Ontario, Canada, a subject of the King of Great Britain, have invented 5 certain new and useful Improvements in Cylindrical Grinding Tools, of which the following is a specification.

This invention relates to rotary tools for 10 truing motor cylinders of the type in which a plurality of abrasive bars are employed operating simultaneously on the whole or a considerable length of the bore of the cylinder, and which are sometimes 15 referred to as cylindrical honing tools, and my object is to devise a tool of this type which is automatically adjustable to cylinders of different diameters and in which the abrasive bars, though resiliently 20 pressed towards the work, are held at all times in absolute parallelism to the axis of the tool, and therefore grind or hone the cylinders true to their longitudinal contours.

25 I attain my object by means of the constructions hereinafter described and illustrated in the accompanying drawings in which—

Fig. 1 is a side elevation of a cylindrical 30 grinding tool constructed in accordance with my invention;

Fig. 2 a cross section of the same on the line 2—2 in Fig. 1; and

Fig. 3 a longitudinal section of part of 35 the tool.

In the drawings like numerals of reference indicate corresponding parts in the different figures.

1 is the body of the tool and 2 holders 40 for the bars 3 of abrasive material. These bars are preferably rectangular in cross section and fit the holders fairly closely, being secured in position by means of set screws 4. The holders are formed on or 45 rigidly connected with pairs of laterally extending rock arms 5, which arms are hinged on axes parallel to the axis of the body by means of the hinge pins 6 passing through lugs 7 formed on the body. The 50 parts are accurately and closely fitted so that the holders, and therefore the bars, swing in and out substantially in exact parallelism to the axis of the body. Spring means are provided for pressing the holders 55 outwardly. While various arrangements might be employed for this purpose

I prefer the construction shown more particularly in Figs. 2 and 3 of the drawings. In a recess extending longitudinally of the body I locate a coil spring 8, one end of this spring being suitably anchored as, for example, by engaging one end of the stem 9 threaded through a hole in the body and adjustable by means of the slotted head 10, by means of which the tension of the spring may be varied. The other end of the spring is engaged, preferably through the medium of a sliding disk 14, with a plurality of bell crank levers 11 suitably located in recesses formed in the body of 70 the tool. These levers are fulcrumed on pins 12 secured in position on lugs 13 formed on the body 1. Each bell crank lever has its end projecting under the adjacent holder 2. The holders are thus 75 simultaneously and equally pressed outwards by the action of the spring 8 and the outward pressure may be varied by adjusting the threaded stem 9.

What I claim as my invention is:—

1. A grinding tool for motor cylinders, including a body, spaced elongated abrasive members surrounding the body, means to connect each end portion of each member to the body for swinging movements transverse to the axis of the body so as to retain the members parallel to the body in all positions of the members, means engaging the respective members between their ends to effect swinging movements 90 thereof, and unitary means for exerting yielding outward pressure against each of the last named means.

2. A cylindrical grinding tool comprising a body; a plurality of holders for narrow abrasive bars extending parallel to the axis of the body; a pair of arms rigidly connected with each holder and extending laterally therefrom; hinged connections between the arms and the body, the axes of the hinges being in alinement and parallel to the axis of the body and close to a circle contacted by the working faces of the abrasive bars, said body having a recess formed therein; a spring located in said recess; and means engaged by the spring and engaging the holders to press them outwardly.

3. A cylindrical grinding tool comprising a body; a plurality of holders for narrow abrasive bars extending parallel to the axis of the body; a pair of arms rigidly connected with each holder and extending laterally

therefrom; hinged connections between the arms and the body, the axes of the hinges being in alinement and parallel to the axis of the body and close to a circle contacted by the working faces of the abrasive bars, spring means tending to press said holders outwardly; and means for adjusting the tension of the spring means.

4. In a device of the type set forth, a body, a series of holders extending axially of the body, abrasive members carried by the holders, means to pivotally connect the holders to the body to allow the holders to swing transverse to the axis of the body, controlling means for each holder pivoted to the body and each having a free part wipingly engaging the holder at a point between the periphery of the body and the bottom face of the holder, and means to tension the controlling means to cause the latter to force the holders outwardly from the body.

5. In combination with a body having a central recess and peripheral slots, holders mounted on the body for outward movement relative thereto, controlling means for each holder mounted in the respective slots of the body and having parts extending into said recess, and means mounted in the recess of the body to tension the controlling means.

6. In a device of the class described, a rotatable body, elongated abrasive members connected to the body lengthwise thereof in spaced relation therearound for swinging movements transverse to the axis of rotation of the body, the abrading surface of the members being retained parallel

to the body axis in all positions of swinging movements of the members, and a single means carried by the body and acting on the several members to exert a yielding predetermined outward swinging pressure thereagainst.

7. In a device of the class described, a rotatable body, elongated abrasive members connected to the body lengthwise thereof in spaced relation therearound for swinging movements transverse to the axis of rotation of the body, the abrading surface of the members being retained parallel to the body axis in all positions of swinging movements of the members, and a single spring means carried by the body and acting on the several members to exert a limited uniform outward swinging pressure against the members and adjustable to vary the limits within which the spring means acts on the members.

8. In a device of the class described, an axially socketed rotatable body, elongated abrasive members carried by the body lengthwise of its axis and in different radial planes for swinging movements transverse to the body axis in permanent parallel relation thereto, and tension means housed in the body in engagement with respective members to exert a uniform outward swinging pressure thereagainst.

Signed at Toronto, Canada, this 25th day of August, 1922.

ERNEST AUSTIN HALL.
